RECIPROCALE RETORT BASE

Thomas George William Watson, Brookman's Park, England, assignor to Taylor Stoker Company Limited, London County, England, a British Company

Application June 27, 1942, Serial No. 448,776
In Great Britain October 6, 1941

15 Claims. (Cl. 110—44)

This invention relates principally to the construction of the bottom of the retorts in stokers of the underfeed type but is also applicable to other apparatus within which it is desired to feed granular or semi-fluid material and has for its object the provision of an improved means for actuating the movement of the firebed on such stokers or for actuating the movement of the material on such other apparatus. The invention will hereinafter be described with reference to underfeed stokers with which it is more particularly concerned.

In underfeed stokers the bottom of the retorts usually consist of horizontally reciprocating pusher blocks arranged alternately with fixed plates and the whole is in stepped formation.

The movement of the fuel within the retorts and of the superimposed firebed depends on a continuing sequence of action wherein there is advancement of fuel by the pusher blocks on their forward stroke and a collapse of fuel into the space created by the fuel so advanced and the face of the pusher blocks on their return stroke. Thus the movement of the firebed depends on the effective collapsing of the fuel in front of the face of each pusher block on its return stroke.

The principal object of the present invention is to provide a means whereby positive and uninterrupted motion can be imparted to the firebed at all times and without being dependent upon effective collapse of fuel in front of the face of the actuating elements on their return stroke.

According to the invention the bottom of the retort is in sections and each of the sections comprises a reciprocable base element incorporating a retractable plate, means being provided whereby the plate is raised prior to the forward movement of the base element and is retracted prior to the return movement of the base element. When the plate is raised it passes upwards through the fuel so that there is no possibility, during its subsequent forward motion, of the plate not exerting a positive movement on the fuel which exists in front of it in solid condition. When at the end of the forward movement of the base, the plate is retracted, the thin space which it originally occupied is readily filled either by the natural collapse of fuel from both front and rear sides or by the assisted collapse which would be caused by the retractable plate when it passes through the fuel prior to its next forward motion.

The accompanying drawings show how the invention may be carried out in practice. Figure 1 shows a section through a base element a number

5 of which are to form the base of a retort for an underfeed stoker. Figure 2 shows a plan of the element. Figure 3 is a section on the line III—III of Figure 1, showing how the base element is supported at each side by a rail fixed to the wall of the retort. Figure 4 is a section taken on the lines IV—IV of Figure 1. Figure 5 is an oblique projection of the base element.

10 The base element is made up of three sections 1 which are bolted together as shown in the drawings. The middle section is provided with a slot 2 extending across the width of the said section and two side plates 3 are formed at the sides of this section and are integral therewith. These 15 side plates travel along the side walls of the retort as the base element moves and they are provided with bevelled edges 3^a and strengthened with horizontal fins 3^b so as to offer the minimum of resistance to the fuel, as can be seen from Figure 2. The purpose of these plates is to provide a guide for the retractable plate 4 and with this 20 object a groove 5 is provided in each plate, the grooves being in alignment with the slot 2. The plate 4 as it rises vertically through the slot is guided and held at its sides in the said grooves. The slot 2 is provided with removable cover plates 2^a for holding packings 2^b in position. These 25 packings serve to prevent fine fuel sifting down through the slot.

30 The retractable plate 4 is supported at its lower end by a double link 6 to which it is pivoted, the other end of the link being pivoted to one arm 7 of a bellcrank lever 8 which is pivoted on a pivot pin 9 which is supported by walls 10 extending from beneath the base element and forming a 35 part thereof, as shown in Figure 5. The other arm 11 of the bellcrank lever is pivoted on the pin 12 to a link 13 which is in turn pivoted to an operating lever 14 pivoted on the pin 15 which is supported by bearings 16. The bearings 16 are 40 bolted to the walls of the retort and are therefore stationary; only one of these bearings is shown in Figure 5 but it will be understood that the pin 15 is supported by a bearing 16 at each end thereof. Power is supplied through a link 17 pivoted to the lower end of the operating lever 14.

45 Figure 3 shows how the base element is supported. Running along the walls 18 of the retort in a horizontal direction are rails 19 which are bolted at intervals to the walls by means of bolts 20. The edges of the base element are shaped as shown to run along the rails, additional security being provided by strips of plates 21 bolted to the underneath side along the said 50 edges.

Assuming that the base element is at the rear end of its stroke with the plate 4 retracted as shown in Figure 1, on the operation of the link-work the lever 14 will be turned in a counter-clockwise direction by the pull of the link 17, the bellcrank lever 8 will be turned in the same direction and the plate 4 will be raised, the base element meanwhile remaining stationary. When the plate has been raised the required amount the faces 22 on the arm 11, which is forked, of the bellcrank lever will abut the tops of the two similarly placed bolts 23 on the base element the position of which bolts can be adjusted each by a head 24 and lock nut 25. Further pull upon the bellcrank lever will thereafter be transmitted through the bolts 23 to the base element which is then caused to move forward, i. e., to the left as shown in Figure 1. To obviate the possibility of the base element tending to move forward prior to the retractable plate 4 being raised two similar counter-weighted levers 26 are mounted on the pivot pin 9. Each lever 26 is counter-weighted by reason of the fact that the end 27 thereof is larger than the end 28. During the period when the plate 4 is being raised the levers 26 are substantially horizontal with the two lighter ends 28 abutting two stationary stops 29. These stops are screwed in similar positions each to one of the two opposite walls of the retort. The said stops then prevent any forward movement of the base element with the result that all motion is directed to the plate 4 until it is raised to its upper limit. As this occurs, adjustable stops 30 on the bellcrank lever 8 meet the lugs 31 on the counter-weighted levers 26 and push the levers 26 round on their pivot and so push the ends 28 of the said levers away from the stationary stops 29. The base element is then free to move and is pulled along by the pull of the link 13 the force being transmitted through the pivot pin 12 to the faces 22, the stops 23, and so direct to the base element. During this movement the ends 28 of the levers 26 slide under the stops 29.

On the return movement, the linkwork is operated in the reverse direction and the first effect will be to lower the plate 4 during which time the base element will not move. When the plate 4 has been lowered to the position where its top edge is flush with the upper surface of the base element the faces 22^a on the arm 11 will meet an opposing wall 22^b below the base element. On further movement of the linkwork the pressure will be transmitted through the said wall 22^b to the base element which will then move in the reverse direction, i. e., to the right as viewed in Figure 1, and when the base has reached the limit of its return travel the counter-weighted ends 27 of the levers 26 will, by their weight, cause the other ends 28 thereof to resume the position where they abut the stationary stops 29, as shown in Figure 1.

The bottom of each retort will be constituted by several such base elements the forward end of each, apart from the last one, overlapping the rear end of the base element in front of it, as indicated in Figure 1. Since the front edges of the elements are not necessarily employed for the purpose of pushing the fuel forward the elements need not be of greater thickness than that necessitated by considerations of strength of construction and it is not necessary to have fixed plates between the base elements. Consequently, the fall in the level of the retort bottom from front to rear of the stoker can, if desired, be relatively small.

Apart from its use in retorts of underfeed stokers the invention can be applied to the mechanism for feeding fuel from the hopper outlets into the throats of the retorts. In fact, the invention can be embodied in any type of trough or other apparatus within which it is desired to impart a forward feeding action to any type of granular or semi-fluid material.

What I claim is:

10. 1. In a stoker, a reciprocable base element for the bottom of the stoker retort, the said element incorporating a retractable plate movable perpendicularly to said element and operable between a raised position in which said plate projects upwardly from said element and a retracted position in which the upper edge of said plate is lowered to said element and means for operating said plate to its raised and lowered positions, said plate operating means and said base element having cooperating means engaging to shift said element in the direction toward the ash pit whereby fuel is advanced by said plate when said plate is in raised position and to return said element when said plate is in lowered position.
15. 2. In a stoker, a reciprocable base element for the bottom of the retort, the said element incorporating a retractable plate and having a slot for the plate extending across the width of the element, operating means for said plate arranged to raise the plate through the slot prior to the forward movement of the element toward the ash pit whereby the fuel is advanced by said plate and to lower said plate through the slot prior to the return movement of the element, said plate operating means forming part of the underneath part of the element.
20. 3. A stoker according to claim 2, wherein the slot is provided with packing to prevent fine fuel sifting between the slot and the plate.
25. 4. A stoker according to claim 2, wherein the element has side plates mounted at the sides thereof and extending above the upper surface of the element adjacent to the slot, the said side plates having grooves in alignment with the slot acting as guides for the retractable plate.
30. 5. A stoker according to claim 2 having side plates mounted at the sides thereof and extending above the upper surface of the element adjacent to the slot, the said side plates having bevelled edges and horizontal reinforcing fins and having grooves in alignment with the slot acting as guides for the retractable plate.
35. 6. In apparatus having a trough within which it is desired to impart a forward feeding action to material, a reciprocable base element for the bottom of the trough, the said element incorporating a retractable plate, means to raise the plate to extend upwardly from said element prior to movement of the said element in one direction whereby the material is advanced by the plate, and means to retract the plate to a position in which the material is not engaged prior to the return movement of the said element.
40. 7. In a stoker, a reciprocable base element for the bottom of the retort, said element incorporating a retractable plate movable perpendicularly to said element and means for operating said plate to raised and lowered positions, said plate operating means comprising a link mechanism having means disengaged from said element throughout movement of said plate with respect to said element and engaged with said element at completion of each movement of said plate with respect to said element to shift said

element upon further operation of said link mechanism, said plate operating means raising said retractable plate before moving said element forward toward the ash pit and lowering said retractable plate before moving said element away from the ash pit.

8. In a stoker, a reciprocable base element for the bottom of the retort, said element incorporating a retractable plate movable perpendicularly to said element, means for operating said plate to raised and lowered positions, said plate operating means comprising a link mechanism having a member operable in opposite directions, spaced parts on said base element engaged by said member for operation of said element, said spaced parts permitting said member free movement between two positions of said member, said member engaging one of said spaced parts upon completion of each movement of said plate with respect to said element to shift said element upon further operation of said link mechanism, said plate operating means raising said retractable plate before moving said element forward toward the ash pit and lowering said retractable plate before moving said element away from the ash pit.

9. In a stoker, a reciprocable base element for the bottom of the retort, said element incorporating a retractable plate movable perpendicularly to said element, means for operating said plate to raised and lowered positions, said plate operating means comprising a link mechanism having a member operable in opposite directions, spaced parts on said base element engaged by said member for operation of said element, said spaced parts permitting said member free movement between two positions of said member, said member engaging one of said spaced parts upon completion of each movement of said plate with respect to said element to shift said element upon further operation of said link mechanism, said plate operating means raising said retractable plate before moving said element forward toward the ash pit and lowering said retractable plate before moving said element away from the ash pit, and an adjustable stop on one of said parts for adjusting the free movement of said member between said parts before operation of said element by said member whereby to adjust the extent of the movements of said retractable plate by said plate operating means prior to operation of said base element by said plate operating means.

10. In a stoker, a reciprocable base element for the bottom of the retort, said element having spaced similarly directed projections and incorporating a retractable plate movable perpendicularly to said element, means for operating said plate to raised and lowered positions, said plate operating means comprising a link mechanism including a bell crank lever with an arm having free angular movement from one to the other of said spaced projections, said arm engaging one of said projections at the completion of each movement of said plate with respect to said element to shift said element upon further operation of said link mechanism whereby during movements of said arm between said spaced projections said retractable plate is operated while said element remains at rest.

11. In a stoker, a reciprocable base element for the bottom of the retort, said element incorporating a retractable plate movable perpendicularly to said element, means for operating said plate to raised and lowered positions, said plate

operating means comprising a link mechanism having means disengaged from said element throughout movement of said plate with respect to said element and engaged with said element at completion of each movement of said plate with respect to said element to shift said element upon further operation of said link mechanism, said plate operating means raising said retractable plate before moving said element forward toward the ash pit and lowering said retractable plate before moving said element away from the ash pit, detent means for preventing said element being prematurely moved forward during the raising of said retractable plate and means on said link mechanism for operating said detent means to release said element as the raising of said retractable plate is completed.

12. In a stoker, a reciprocable base element for the bottom of the retort, said element incorporating a retractable plate movable perpendicularly to said element, means for operating said plate to raised and lowered positions, said plate operating means comprising a link mechanism having means disengaged from said element throughout movement of said plate with respect to said element and engaged with said element at completion of each movement of said plate with respect to said element to shift said element upon further operation of said link mechanism, said plate operating means raising said retractable plate before moving said element forward toward the ash pit and lowering said retractable plate before moving said element away from the ash pit, a stop member fixed to a stationary part of the retort, a movable member carried by said element and adapted to engage said stop member to prevent said element being prematurely moved forward during the raising of said retractable plate and means on said link mechanism operating said movable member to disengage said movable member from said stop member to release said element as the raising of said retractable plate is completed.

13. In a stoker, a reciprocable base element for the bottom of the retort, said element incorporating a retractable plate movable perpendicularly to said element, means for operating said plate to raised and lowered positions, said plate operating means comprising a link mechanism having means disengaged from said element throughout movement of said plate with respect to said element and engaged with said element at completion of each movement of said plate with respect to said element to shift said element upon further operation of said link mechanism, said plate operating means raising said retractable plate before moving said element forward toward the ash pit and lowering said retractable plate before moving said element away from the ash pit, a stop member fixed to a stationary part of the retort, a movable member carried by said element and adapted to engage said stop member to prevent said element being prematurely moved forward during the raising of said retractable plate, said movable member being biased to engage said stop member, and a second means on said link mechanism operating said movable member to disengage said movable member from said stop member to release said element as the raising of said retractable plate is completed, said movable member being released by said second means when said plate is retracted.

14. In a stoker, a reciprocable base element for the bottom of the retort, said element incorporating a retractable plate movable perpendicularly to said element, means for operating said plate to raised and lowered positions, said plate

larly to said element, means for operating said plate to raised and lowered positions, said plate operating means comprising a link mechanism having means disengaged from said element throughout movement of said plate with respect to said element and engaged with said element at completion of each movement of said plate with respect to said element to shift said element upon further operation of said link mechanism, said plate operating means raising said retractable plate before moving said element forward toward the ash pit and lowering said retractable plate before moving said element away from the ash pit, a stop member fixed to a stationary part of the retort, a lever mounted on said element and adapted to engage said stop member to prevent said element being prematurely moved forward during the raising of said retractable plate, and a second means on said link mechanism for operating said lever to disengage said lever from said stop member to release said element as the raising of said retractable plate is completed, said lever being freely pivoted and having a counterweighted end whereby said lever is caused to return to a position engaging said stop member and preventing movement of said element when released by said second means and said element reaches the end of its stroke away from said ash pit.

15. In a stoker, a reciprocable base element for the bottom of the retort, said element incorporating a retractable plate movable perpen-

dicularly to said element, means for operating said plate to raised and lowered positions, said plate operating means comprising a link mechanism having means disengaged from said element throughout movement of said plate with respect to said element and engaged with said element at completion of each movement of said plate with respect to said element to shift said element upon further operation of said link mechanism, said plate operating means raising said retractable plate before moving said element forward toward the ash pit and lowering said retractable plate before moving said element away from the ash pit, a stop member fixed to a stationary part of the retort, a lever mounted on said element and adapted to engage said stop member to prevent said element being prematurely moved forward during the raising of said retractable plate, and a second means on said link mechanism for operating said lever to disengage said lever from said stop member to release said element as the raising of said retractable plate is completed, said lever being freely pivoted and having a counterweighted end whereby said lever is caused to return to a position engaging said stop member and preventing movement of said element when released by said second means and said element reaches the end of its stroke away from said ash pit and a lever pivoted to a stationary part of the stoker for operating said link mechanism.

THOMAS GEORGE WILLIAM WATSON.
